[57] CLAIM

The ornamental design for an amusement device, as shown and described.

DESCRIPTION

FIG. 1 is a perspective view of an amusement device showing my new ornamental design;

FIG. 2 is a top view thereof;

FIG. 3 is a bottom view thereof;

FIG. 4 is a frontal elevation thereof;

FIG. 5 is a rear elevation thereof; and,

FIG. 6 is a side elevation thereof, the other side view thereof being the mirror image thereof.
